OPTICAL SLIT

Michael Bowman-Manifold, Worplesdon, England, assignor, by mesne assignments, to Radio Corporation of America, New York, N. Y., a corporation of Delaware

Application June 11, 1929, Serial No. 370,113
In Great Britain July 16, 1928

5 Claims. (Cl. 179—100.31)

The present invention relates to optical slits such as may be used in recording and reproducing sounds.

The invention is applicable whether the record 5 in question is actually a record of sounds or whether it is a record of any other relatively low frequency oscillations.

When a record of the modulations of intensity of a beam of light is made upon a travelling photographic film, the record being in the form of variations in density of the film, it is well known 10 that the light should be caused to fall upon the sensitive surface in the form of a thin line transverse to the direction of movement of the film. 15 The same applies where the record produced is in the form of variations in breadth of a band of constant density. In order to obtain a uniform photographic effect (disregarding the sensitivity of the film) at all frequencies, it would 20 be necessary to use a line of infinitesimal width, and even to obtain uniformity over the important acoustic range of frequencies, a very thin line is required, with consequent reduction in the total light falling upon the sensitive 25 surface.

It will be found, for example in reproducing, that when the ripple wave length of the record (that is to say, in a varying density record, the distance along the film between successive maximum or minimum densities) co-operating with 30 a slit is equal to the width of the slit, the overall effect upon the beam of light transmitted through the record is zero, that is to say the response curve falls to zero. As the ripple wave-length is 35 reduced, the response curve rises to a secondary maximum which, although considerably below the height of the response curve at low frequencies, is, nevertheless, of considerable importance. With further reduction in ripple wave length, the 40 response curve falls again to zero and then rises to a tertiary maximum and so on, the amplitude of successive maxima gradually falling. The same effect exists when reproducing from a varying breadth record, the ripple wave-length in that case being the distance between successive peaks.

It is an object of the present invention to reduce the magnitude of the secondary maximum.

In any photographic record, there will be 50 found to be a series of absent frequencies corresponding to the frequencies at which the response characteristic, in making the record, fell to zero. According to the present invention, the frequency at which the secondary maximum of 55 the reproducing characteristic occurs is made

substantially to coincide with the lowest absent frequency of the record. Alternatively, the frequency at which the first zero of the reproducing characteristic occurs is made substantially coincident with the frequency of the secondary maximum of the record.

This may be accomplished by making the width of the slit used in reproducing from a photographic record different from the width of the slit which was used in making the record. One 60 of the slits is preferably 1½ times as wide as the other. The ratio of the widths may vary somewhat from this figure but it should be between 1¼ and 1¾. It should be understood that it is intended that the word "slit" in this specification be given a wide interpretation as it is immaterial whether a physical slit in close proximity to the record is used or whether the effect of a slit is produced by optical means as, for example, by projecting upon the film an image 70 of a slit placed at a distance from the film.

The invention will be better understood in the light of the following explanation: For simplicity, the description will be confined to records of varying intensity and constant breadth but 80 it will be understood that the description is also applicable to records of varying breadth, the expression "density of the record" being replaced by "breadth of the blackened portion of the record".

If a light beam, fully modulated at an acoustic frequency, falls through a slit of infinitesimal width upon a moving photographic film, the density of the record produced is represented by the 85 equation:

where

$$x = a (\cos \omega s + 1) \quad (1)$$

x is the film density

a is a constant for any given type of film and 95 illumination.

s represents distance measured along the film in its direction of movement

and

$$\omega = \frac{2\pi}{\lambda}$$

where λ is the ripple length of the record.

With a slit of finite width equal to d , the resulting density is equivalent to that which would be 105 produced by a series of infinitesimal slits extending from

$$\left(s - \frac{d}{2} \right) \text{ to } \left(s + \frac{d}{2} \right)$$

110

and therefore

$$5 x = a \int_{s-\frac{d}{2}}^{s+\frac{d}{2}} (\cos \omega s + 1) ds = \frac{a}{\omega} \left[\sin \omega \left(s + \frac{d}{2} \right) - \sin \omega \left(s - \frac{d}{2} \right) \right] + ad \quad 80$$

$$x = \left[\frac{2a}{\omega} \cos \omega s \sin \frac{\omega d}{2} \right] + ad \quad (2) \quad \text{(which is negative) of the expression}$$

10 The modulation Z represented by equation (1) is unity and that represented by equation (2) is equal to

$$15 Z = \frac{2a \sin \frac{\omega d}{2}}{ad\omega} \quad 85$$

which may be written

$$20 \frac{\sin \frac{\omega d}{2}}{\frac{\omega d}{2}} \quad 90$$

This is illustrated in the dotted curve A in the accompanying drawing, the response or modulation being plotted vertically and

$$\frac{\omega d}{2}$$

30 horizontally. Unit modulation is represented by the horizontal line a. The response is plotted in transmission units which are proportional to the logarithm of the modulation.

35 Since the same effect takes place upon reproduction, the overall degree of modulation, when the slit used is of the same width for reproducing as for recording, will be

$$40 Z^2 = \left[\frac{\sin \frac{\omega d}{2}}{\frac{\omega d}{2}} \right]^2 \quad (3) \quad 105$$

This is shown in the plain line curve B of the drawing, in this case Z^2 being plotted vertically in transmission units. As

$$\frac{\omega d}{2}$$

45 increases from 0 to π , Z^2 falls gradually from unity to zero and as

$$\frac{\omega d}{2}$$

50 is still further increased Z^2 rises to a secondary maximum at a value of

$$\frac{\omega d}{2}$$

55 slightly less than

$$\frac{3}{2}\pi$$

A series of maxima of decreasing height are in fact obtained with increasing values of

$$\frac{\omega d}{2}$$

but the one referred to as the secondary maximum is the most important. By making

$$d_1 = \frac{3}{2} = d_2$$

(where d_1 is the slit width used in recording and d_2 that for reproducing) equation (3) becomes

$$70 Z^2 = \left[\frac{\sin \frac{\omega d_1}{2}}{\frac{\omega d_1}{2}} \right] \left[\frac{\sin \frac{\omega d_1}{3}}{\frac{\omega d_1}{3}} \right] \quad 145$$

and it will be found that the secondary maximum

$$\frac{\sin \frac{\omega d_1}{2}}{\frac{\omega d_1}{2}}$$

is substantially opposite to the first zero point of the expression

$$\frac{\sin \frac{\omega d_1}{3}}{\frac{\omega d_1}{3}} \quad 95$$

and the value of the secondary maximum is consequently reduced. The same applies, of course, if

$$d_1 = \frac{2}{3} d_2 \quad 100$$

105 The overall response when using slits in recording and reproducing respectively in the ratio 3:2 or 2:3 is shown in chain dotted curve C of the drawing, d being, in this case, the width of the wider slit. If curve C be compared with curve B, which is the equivalent curve for equal slits, it will be seen that in curve C the maxima and minima are less pronounced than in curve B.

I claim:

110 1. Apparatus for reproducing sound or other low frequency oscillations from a record of said oscillations with the aid of light comprising a moving photographic record, a light source, and a slit device, said device being so proportioned that the frequency at which the secondary maximum of the characteristic of the reproducing apparatus occurs is made substantially to coincide with the lowest absent frequency of the record.

115 2. Apparatus for reproducing sound or other low frequency oscillations from a record of said oscillations with the aid of light comprising a moving photographic record, a light source, and a slit device, said device being so proportioned that the lowest frequency at which the response of the reproducing apparatus is zero is made substantially to coincide with the frequency of the secondary maximum of the record.

120 3. Apparatus for reproducing sound or other low frequency oscillations from a record of said oscillations with the aid of light wherein a slit is used having a different width from that used in making the record, the width of one of said slits being in a ratio not less than 5:4 nor more than 7:4 to the width of the other of said slits.

125 4. Apparatus for reproducing sound or other low frequency oscillations from a record of said oscillations with the aid of light wherein a slit is used having a different width from that used in making the record, the width of one of said slits being substantially in the ratio 3:2 to the width of the other of said slits.

130 5. Apparatus for reproducing sound or other low frequency oscillations from a record of said oscillations with the aid of light wherein a slit is used having a different width from that used in making the record, the width of the slit used in making the record being in the ratio 3:2 to the width of the slit used for reproducing from said record.
